UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

WIRING DEVICE.

1,033,948.

Specification of Letters Patent. Patented July 30, 1912.

Application filed June 6, 1910. Serial No. 565,224.

To all whom it may concern:

Be it known that I, ARTHUR L. RUSSELL, a citizen of the United States, residing at Hyde Park, in the county of Norfolk and State of Massachusetts, have invented certain Improvements in Wiring Devices, of which the following description, in connection with the accompanying drawings, is a specification, like reference characters on the drawings indicating like parts in the several figures.

This invention relates to wire anchoring apparatus and has for one object to provide improved means for anchoring a wire to a tack or the like.

Another object is to provide means by which a wire can be placed and tightened into binding relation to the work, as for example, about the toe portion of a lasted shoe, and then anchored while held under tension.

A further object is to provide a hand tool by which a workman can string a wire about the toe of a shoe in the process of lasting and drive a tack and anchor the wire.

An important feature of the invention consists in means for holding a wire adjacent to a tack stem or to the path of an incoming tack and means actuated by the downward movement of the tack driver or the like for wrapping the wire around the stem of the tack. Heretofore it has been proposed to bend a wire around a tack by force applied in the plane in which the wire was to be bent or in a plane parallel thereto but in accordance with this feature of the invention the wire bending movement is taken from a member moving perpendicularly to the plane of the wire.

In the preferred embodiment of this invention the apparatus includes a tacker, the driver of which acts through a spiral or inclined connection with a sleeve to twist the wire around the tack which is being inserted. It may, however, be embodied without further invention in an apparatus which will wrap the wire around a previously driven tack.

A further feature of the invention is found in means constructed and arranged for use in carrying a wire around the object to be bound and having means for anchoring the wire. Preferably said wire carrying means will be formed to adapt it to place a

wire under tension in holding relation to the work, as for example, between the retracted 55 wipers and the upstanding upper materials of a lasted shoe toe. As herein shown, the wire carrying means is a part of or an attachment to a hand tacker, the nozzle of which is employed for placing the wire 60 and the wire bender is turned about the nozzle to wrap the wire around the stem of the tack as the tack is being driven.

A further feature of the invention is found in a wire tension device mounted to 65 move with the wire carrier in placing the wire around the work. Preferably also the wire tension device moves with the bender in wrapping the wire around the tack. As herein shown the tension device accompanies 70 the bender in its rotary movement and in accordance with a further feature of this invention a wire cutter is interposed in the path of the strand of wire which extends from the bender to the tension device to cut 75 the wire automatically when it has been partially wrapped around the tack.

These and other features of the invention, including certain details of construction and combinations of parts will more fully appear 80 in connection with the following description of a preferred embodiment of the invention and will then be pointed out in the claims.

Figure 1 is a perspective view showing the 85 toe portion of a shoe in a bed lasting machine, the lasting wipers being partially retracted to permit a wire to be carried around the lasted toe by the nozzle of a hand tacker equipped with wire anchoring 90 means embodying this invention; Fig. 2 is a longitudinal sectional view of the tacker and wire anchoring attachment; Fig. 2^a is a transverse section on line 2^a showing a modification; Fig. 3 is a perspective view of the 95 lower end of the apparatus; Fig. 4 is a perspective detail, and Fig. 5 is a perspective detail from a different angle.

1 indicates a casing of a hand tacker which may be in general construction substantially 100 like that shown in United States Letters Patent No. 500,225, granted on application of Crisp and Judkins June 27, 1893. This casing comprises a cylindrical driver guide having a lateral extension or bracket 2 to 105 which is attached the raceway 4 in which

tacks are held and conducted to the driver passage, a gate 5, operated by the wedge bar on the driver plunger 6, being located at the foot of the raceway as shown in the sectional view, Fig. 2. These parts, together with the spring 8 inclosed within the driver plunger and resting at the lower end upon the cross bar 10 that extends from one side of the casing through slots in the plunger to the other side may be the same as in said patent.

Rotatably mounted within the cylindrical driver guide is a sleeve 20 having a slot 22, the lower portion of which is oblique or spiral and in this slot moves a roller stud 24 which projects laterally from the driver plunger 6, see dotted lines Fig. 2. By this arrangement the sleeve 20 is automatically given a partial rotation during the last or tack driving portion of the driver movement. The roller stud may be connected to the driver plunger yieldingly as by a circumferentially movable block 23, Fig. 2^a, to lessen the shock when the roller enters the spiral portion of the slot in the sleeve.

Attached to the sleeve 20 is an arm 25 which projects through a circumferentially elongated opening in the casing and which is bowed around those portions of the tacker which include the tack feeding devices and has on its lower end a ring 26 provided with a toothed interior face. These teeth mesh with a small pinion 28 which is fastened, Figs. 4 and 2, to or formed integral with a wire twisting sleeve 30 which turns around the nozzle 12 of the tacker. This twisting sleeve has a wire finger 35 by which it engages the wire, assisting to determine its normal position with relation to the tack passage, and compelling the wire to be carried around the stem of the tack when the driver in its descent causes the rotation of said sleeve. The arm 25 carries a tension device 36 between which and the finger 35 the course of the wire is determined and on the lower end of the casing are mounted the open jaws 38 of a wire cutter. This cutter is located in the path of the wire as it is carried around the nozzle by the rotation of arm 25 and sleeve 20. These jaws are pivoted on different centers, as shown in Fig. 3, which are so located that pressure of the wire into the angle between them turns them toward each other in a direction to sever the wire. The lower end of the sleeve 30 is beveled at 40 so that as the sleeve is turned in the direction of the arrow, Fig. 4, the wire is automatically crowded down toward the shoe. A wire supply holder may be detachably mounted on the tacker. This holder comprises the plate 46 fast to the casing 1 and having the series of out-turned fingers or flanges. The outer flange 48 supports the coil of wire and has a bead on its edge which interlocks with the correspond-

ing fingers of the cover plate 49. The flange 47, together with a similar flange on the cover plate, prevents the wire from becoming entangled as it is unwound from the inside of the coil. Each of these inner flanges is turned inwardly at its edge to present between the two flanges a continuous guideway for the unwinding wire. This tacker with the wire anchoring attachment may be used, if desired, in the customary way to insert the lasting tacks for securing the upper at the heel as well as an anchor tack *t* in the upper side of the shoe at the toe. The wire is applied to the apparatus by inserting the coil in the holder and passing the end of the wire under the tension device which may be opened to receive it by pressing upon its rear end, Fig. 3. The free end of the wire having been hooked over the finger 35 may then be twisted around the tack by using the tacker 3 as the lasting machine operators are accustomed to use their hand pincers for this purpose. Then the wire is strung or drawn under tension about the toe of the shoe, the wipers 41, Fig. 1, being backed partially away from the upstanding upper material to permit this placing of the wire which is very conveniently effected by the nose of the tacker. The wire might come through the tension device from a reel mounted on a stationary support like the frame of the lasting machine if that were preferred. At the second side of the shoe where the tacker is shown in Fig. 1, the wire is pulled tight by means of the tacker and then with the nozzle resting on the shoe the driver plunger is forced down to insert the second wire anchoring tack by impact. In the last part of this movement the roller stud 24 enters the spiral part of the slot 22, turning the sleeve 20, arm 25 and sleeve 30, and causing the wire finger 35 to carry the wire under tension around the stem of the ingoing tack while the bevel on the end of sleeve 30 forces the wire down toward the shoe. The tack may be left slightly upstanding or may be fully driven, but in either case the twisting sleeve insures that the wire shall be wrapped around the tack stem under its head and close to the surface of the work. As the twisting devices rotate and the tension device 36 with them, although more slowly, the wire between the finger 35 and the tension engages the cutters 38 and is severed from the supply. The devices are shown as arranged to give to the sleeve 20 a rotary movement of 90° which is multiplied by the pinion 28 to give the twisting sleeve 30 a half rotation. This carries the end portion of the wire back to the body of the binder.

By the use of this invention in which the wire is wrapped about the ingoing tack close to the work a shorter and more slender tack can be used than is necessary to use in

hand wiring and such a light tack can advantageously be driven fully into the work so that it is not necessary to wrap the wire many times around the tack, as is done when 5 a long tack is left upstanding half its length from the work. Obviously a greater amount of rotation can be given to the wire twisting sleeve if desired by changing the proportions of the gears 26, 28, or extending 10 the spiral portion of the slot 22.

It will be noted that as the apparatus is used to place the wire around the toe, it can be moved to slide the nozzle between the partially backed off wipers and the upstanding 15 edge of upper that is to be bound in place and the wire will thus be strung around the toe under tension and the finger 35 will place the wire high enough so that it is out of the path of the needle of the sewing machine by which the upper is later 20 fastened permanently to the lip of the insole.

Having explained the nature of this invention and described a preferred embodiment thereof, I claim as new and desire to 25 secure by Letters Patent of the United States:—

1. An apparatus of the class described having, in combination, means for holding a wire adjacent to the stem of a tack projecting from the surface of a shoe, and means movable perpendicularly to the plane 30 of the said surface and operatively connected to the first named means for bending the wire around the tack during such perpendicular movement.

2. An apparatus of the class described having, in combination, means for holding a wire adjacent to the stem of a tack projecting from the surface of a shoe, a driver 40 movable substantially perpendicularly to the plane of said surface and an operative connection between said driver, and means arranged to convert the movement of the driver into a rotary movement of the wire holder around the stem of the tack.

3. An apparatus of the class described having, in combination, a tack driver, a wire bending sleeve and a stud and inclined slot connection between the driver and the sleeve 50 to effect wire bending movement of the sleeve by tack inserting movement of the driver.

4. An apparatus of the class described having, in combination, a tack driver, a wire bending sleeve, and a stud and inclined slot connection between the driver and the sleeve to effect wire bending movement of the sleeve by tack inserting movement of the driver, said apparatus having provision for 55 multiplying the angular movement in its transmission from the driver to the bending sleeve.

5. An apparatus of the class described having, in combination, the driver bar 60 having the stud 24, the sleeve 20 having the

inclined groove for said stud, the wire bending sleeve 30, and the multiplying gears 26, 28, between said sleeves 20 and 30.

6. An apparatus of the class described having, in combination, tack supplying devices, a driver bar having a stud, a sleeve having an inclined slot for producing rotation of the sleeve from movement of the driver and stud, the wire bending sleeve and the arm 25 bowed outwardly around the 70 tack supplying devices and connecting the two sleeves.

7. An apparatus of the class described having, in combination, a tack driver, a wire bending sleeve, means for turning it independent of the driver, and a wire finger projecting laterally from the sleeve.

8. An apparatus of the class described having, in combination, means constructed and arranged for use in guiding and placing 85 a wire progressively around the lasted toe of a shoe from one side around the end to the other side of the toe, and devices mounted thereon for anchoring the wire at said other side after it has been anchored at the first 90 side and tensioned.

9. An apparatus of the class described having, in combination, means constructed and arranged for use in guiding and placing 95 a wire around the lasted toe of a shoe, and devices mounted thereon for driving a tack to anchor the wire and for severing the wire from a strand.

10. An apparatus of the class described having, in combination, a wire bending device adapted to embrace an anchor tack in the lasted shoe and having a wire guide located closely adjacent to the stem of the tack so embraced, means for turning said device to wrap a wire around a tack, and a tension 100 device movable with the bending device.

11. An apparatus of the class described having, in combination, a rotatable wire bending sleeve having a wire finger at its end and located close to the axis of rotation 110 and a wire tension device movable therewith.

12. An apparatus of the class described having, in combination, a tack nozzle, a bending sleeve rotatable around the nozzle, 115 a wire finger to carry the wire around the tack as the sleeve is rotated, and a wire depressor means arranged to follow the finger and press the wire down for causing it to wrap about the stem of the tack below the 120 nozzle.

13. An apparatus of the class described having, in combination, a tacker comprising a driver, and means actuated yieldingly by the driver to bend a wire around the ingoing 125 tack.

14. An apparatus of the class described having, in combination, a carrier adapted to be positioned over a tack, a device thereon to carry a wire around the stem of the tack for 130

- anchoring the wire, means for actuating said device relatively to the carrier, and means arranged with relation to the bending device to maintain substantially uniform tension upon the portion of the wire that is being bent.
15. An apparatus of the class described having, in combination, a wire bending device movable to carry a wire around a tack, a device to hold the wire under tension, and means to move said two devices in the same direction at different speeds.
16. An apparatus of the class described having, in combination, the wire bending sleeve 30 having the wire finger 35, the rotating sleeve 20, the multiplying gearing 26, 28, connecting said sleeves, the tension device 36 carried by the slower moving sleeve 20, and the wire cutters 38 arranged with relation to the tension device and the wire finger to cut the portion of wire being bent from the strand of wire after the wire has been carried far enough around the tack in the bending movement to avoid danger of its slacking back after it is cut.
17. An apparatus of the class described having, in combination, a wire bending device movable to carry a wire around the stem of a driven tack, a wire cutter, and a device movable in the same direction as the bending device and coöperating therewith to carry the end portion of the wire into position to be severed by the cutter.
18. An apparatus of the class described having, in combination, a wire bending device movable to carry a wire around a tack, and a wire cutter arranged in the path of the end portion of the wire which is being carried around the tack but normally out of engagement therewith, and operating to sever the wire from the strand.
19. An apparatus of the class described having, in combination, a wire bending device movable to carry a wire around a tack, and a wire cutter operating automatically to sever the wire when the wire has nearly completed its movement around the tack.
20. An apparatus of the class described comprising a hand tacker adapted for use in inserting lasting tacks and having a wire bending attachment adapted to wrap a wire around the stem of the tack inserted by the tacker while the tacker remains in inserting position.
21. An apparatus of the class described comprising a hand tacker adapted for use in inserting lasting tacks, and having a wire bending device operatively connected to the tack driving mechanism for automatic rotation thereby about the stem of the tack.
22. An apparatus of the class described comprising a hand tacker adapted for use in inserting lasting tacks and having means for guiding and holding a toe binder under tension in predetermined lateral relation to

the tacker and having a prescribed movement to cause the binder to be anchored by a tack inserted by said tacker.

23. An apparatus of the class described comprising a hand tacker adapted for use in inserting lasting tacks and having a binder guide arranged for manipulation by the tacker in placing a binder around the toe end of the shoe.

24. An apparatus of the class described comprising a hand tacker adapted for use in inserting lasting tacks and having a binder guide attached to the tacker nozzle and adapted for manipulation thereby to string a binder around the toe of a lasted shoe between the upstanding upper material to be bound and the partially backed off lasting wipers, and means for relatively actuating the tacking devices and said binder guide to anchor the binder.

25. An apparatus of the class described comprising a hand tacker adapted for use in inserting lasting tacks and having a binder guide arranged for manipulation by the tacker in placing a binder around the toe end of the shoe, and a cutter to sever the binder from a supply of binder material.

26. An apparatus of the class described comprising a hand tacker adapted for use in inserting lasting tacks and having a binder guide arranged for manipulation by the tacker in placing a binder around the toe end of a shoe, and means for applying tension to the binder.

27. An apparatus of the class described having, in combination, means for use in placing a binder about the toe of a shoe under tension and securing it in binding relation to the lasted upper, and means operating automatically while the binder is maintained under tension to sever the binder from a strand of binder material.

28. An apparatus of the class described having, in combination, manual means for placing a binder around the toe of a shoe in binding relation to the lasted upper materials, means for inserting a fastening, and means for automatically anchoring the binder to the tack.

29. An apparatus of the class described having, in combination, manual means for placing a binder around the toe of a shoe in binding relation to the lasted upper materials, and means for anchoring the binder and severing it from a strand of binder material.

30. An apparatus of the class described comprising a hand tacker adapted for use in inserting lasting tacks, and having a binder guide, a tension device, a holder for a supply of binding material, and a binder arranged to be actuated during the tack driving operation to anchor the binder to the inserted tack.

31. An apparatus of the class described

having, in combination, means for use in stringing a wire around the toe of a shoe having a face to engage with the surface of the upper on the margin of the sole, and 5 provision for positioning the wire a predetermined distance above said surface.

32. An apparatus of the class described having, in combination, the sleeve 30 adapted to be moved around a shoe toe for stringing 10 a wire binder in place to hold a lasted upper, the wire finger 35 located above the end of the sleeve to position the wire above the base of the upstanding upper material to be bound in, and the tension device 36 15 to facilitate the application of the wire tightly in binding position.

33. An apparatus of the class described having, in combination, means for holding 20 a wire binder under tension and means for bending the binder around a tack, means for actuating the bending means around the tack and for moving the tension means simultaneously about a different center which is located with relation to the tack

to cause wire to be given up to the bending 25 means as the bending operation proceeds.

34. An apparatus of the class described having, in combination, means for holding a wire binder under tension and means for bending the binder around a tack, said ten- 30 sion means being mounted for movement toward the bending means during the bending operation.

35. An apparatus of the class described having, in combination, means for holding 35 a wire binder under tension and means for bending the binder around a tack, and means for actuating said tension means to cause wire to be given up to the bending 40 means during the bending operation.

In testimony whereof I have signed my name to this specification in the presence of two subscribing witnesses.
